UNITED STATES PATENT OFFICE.

CHARLES E. SANSON, OF EAST SYRACUSE, NEW YORK.

SECTIONAL MOLD FOR MAKING CONCRETE BLOCKS.

Application filed February 10, 1926. Serial No. 87,355.

This invention relates to a device for molding concrete blocks and refers more particularly to a collapsible mold for making hollow cement blocks of uniform size for use in structural concrete building but may be used for making blocks of unequal lengths as, for example, half or three-quarter the standard length for corner finishing.

One of the objects is to make the upright portions of the mold into two sections hinged together at one corner with detachable interlocking connections at the diagonally opposite corner for holding the sections in fixed relation and permitting them to be easily and quickly opened to free them from the molded block when the latter is sufficiently set to retain its shape, the remaining diagonally opposite corner being rigidly held against flexing movement.

Another object is to provide the base section with suitable cores for producing connected openings in each block in such manner that when these blocks are assembled in a wall the openings will communicate with each other for the circulation of air therethrough the length of the wall for ventilating purposes and thereby to reduce the liability of transmission of moisture through the walls.

Another object is to provide the sections of the mold with means to produce beveled corners upon the exposed faces of the blocks and thereby to assure the depression of the joints within said surfaces.

A further object is to enable certain parts of the base section to be easily and quickly changed from one position to another to form the connecting passages between the openings in the blocks, either for straight longitudinal work or for corner turns.

Another object is to provide the mold with interior vertical ribs to form corresponding vertical grooves or channels in the ends or sides of the block to be used as air passages or for the reception of cement at the joints for additionally holding the blocks in proper alignment when the joint cement is set.

Other objects and uses relating to specific parts of the mold will be brought out in the following description.

In the drawings:

Figure 1 is a top plan of a mold embodying the various features of my inven-

tion ready for the reception of the concrete or cement which is to form a block of standard size.

Figures 2 and 3 are sectional views taken respectively on lines 2—2 and 3—3, Figure 1.

Figure 4 is a perspective view of the detached top or cap of the mold.

Figure 5 is a perspective view of the upright sections of the mold unfolded.

Figure 6 is a perspective view of the detached bottom section of the mold.

Figure 7 is a perspective view of an insert section used as a partition when making half block sections.

Figure 8 is a perspective view of one of the supplemental insert sections adapted to be used at the end or side of the mold when forming straight or corner blocks.

Figures 9 and 10 are perspective views of a block of standard size made in my improved mold as seen from the top and from the bottom respectively.

Figure 11 is a perspective view from the underside of a slightly modified form of block made in the mold to be used for corner work.

Figure 12 is a perspective view from the underside of a half block made in the same mold.

As illustrated, this mold comprises a bottom section —1—, opposite side and end sections —2— and —3—, a top section —4—, a partition section —5— and a supplemental insert section —6—, all of which parts may be made of wood or metal or part wood and part metal and are constructed so as to form substantially rectangular blocks as shown in Figures 9 to 12 inclusive.

The base section —1— is rectangular in top plan and of somewhat greater area than the mold to be formed and is provided along its side and end edges with relatively short upstanding lugs —7— in spaced relation for centering, guiding and holding the side and end sections in operative position thereon when the parts of the mold are assembled for use.

This base section —1— is also provided with a pair of core posts —8— extending upwardly from its upper surface a distance corresponding approximately to the vertical depth of the block to be molded, said posts

being arranged in spaced relation along the longitudinal center of said base plate and, therefore, substantially midway between the opposite sides thereof and equal distances 5 from the ends, the distance between the posts from center to center being approximately equal to the transverse distance between the inner faces of the side walls —2— of the mold when the latter are placed in operative 10 position upon the base so as to form corresponding central vertical openings —8— in both halves of the block as shown in Figures 9, 10 and 11 or either one of said posts may be used to form a single central vertical 15 opening —8— in the half block as shown in Figure 12.

A relatively shallow V-shaped rib —9— is mounted upon the upper face of the base plate —1— along the longitudinal center thereof and between the lower ends of the posts —8— to form central lengthwise channels —9'— in the adjacent face of the block connecting the vertical openings —8— for the circulation of air thru said channels and openings when the blocks are assembled in wall construction.

A pair of similar V-shaped ribs —10— are also mounted upon the upper face of the base plate —1— along the longitudinal center thereof as shown in Figures 1, 2 and 6 between the outer faces of the posts and inner faces of the end walls —3— when the latter are placed in operative position on the base plate to form additional similar 35 grooves or channels —10'— in the lower face of the block shown in Figures 9 and 10.

The posts —8— and rib —9— may be permanently secured to the base plate —1— or may be detachably fastened by screws, dowels or any other well-known fastening means if desired.

The rib sections —10—, however, are made detachable from the base plate but are normally held in operative position thereon by screws —11—, Figure 2.

The object of this removability of the rib sections —10— is to permit them to be placed in different positions as, for example, at one side of either of the posts —8— 50 as shown by dotted lines in Figure 1 for the purpose of forming corresponding channels as —10''— leading from the corresponding side of the adjacent post opening —8— to form the block shown in Figure 11 which is adapted to be used at the corner of the wall thereby forming continuations of the channels in the lower sides of the block around said corners.

For this latter purpose the base plate —1— is provided with separate pairs of bolt or screw holes —11'— at opposite sides of each post —8— to enable the ribs —10— to be placed in corresponding positions.

The base plate —1— and top plate —4— are provided with relatively shallow length-

wise ribs —12— projecting inwardly from their inner faces at one and the same side of the posts —8— and in parallel spaced relation to the rib —9— so as to engage the inner face of the adjacent portions of the 70 corresponding side wall —2— when the parts of the mold are assembled for use, the inner faces of said ribs being beveled to form lengthwise beveled edges —12'— on the lower and upper outer corner of the 75 block as shown in Figures 9 to 12 inclusive.

The partition —5— and end plates —6— are also provided with similar vertical ribs —13— secured to the inner faces of the corresponding upright edges to lie in the same 80 vertical plane as the ribs —12— when the sections —5— and —6— are placed in operative position to form beveled corners —13'— at the ends of the outer exposed face of the block as shown in Figures 9 to 85 12 inclusive.

Two of the diagonally opposite corners of the upright walls —2— and —3— of the mold are rigidly connected to each other by angle plates —14— screwed or otherwise 90 secured to the upper edges of adjacent portions thereof thereby forming two similar angular or L-shaped sections of the mold which when brought together form a rectangular frame adapted to rest upon the base section —1— just inside of and against the lugs —7— which aid in centering the frame and holding it in operative position upon the base.

One of the side sections and one of the 100 end sections at one of the remaining corners of the frame are flexibly connected by a hinge —15— whereby the two angular sections are hinged to each other to be opened and closed at will.

The meeting edges of the remaining side and end walls are adapted to open and close about the axis of the hinge —15— but when the various parts of the mold are adjusted for use these portions of the frame are 110 locked in their closed position by locking levers —16— and keepers —17—, the levers —16— being hinged to the free end of the corresponding side section —2— while the keepers —17— are secured to the 115 free edge of the adjacent end section —3— and are slotted to receive the levers —16— which are provided with cams whereby they may be tightened upon their respective keepers to lock the two angular sections of 120 the frame to each other as shown in Figure 1.

One of the side sections opposite that which is engaged by the lengthwise ribs —12— is provided with relatively thin 125 sheet metal lining sections —18— of substantially the same length as the interior width of the mold and, therefore, substantially half the length of said interior.

The end walls —3— are also provided 130

with interior removable metal linings —18'— extending from side to side of the interior of the mold and, therefore, of about the same width as the length of the sections —18— so that they may be interchanged therewith.

These plates —6— are provided on their inner faces with vertical ribs —20— extending from bottom to top thereof in equally spaced relation from opposite sides of the rib —10— to form vertical channels —20'— in the ends of the block as shown in Figures 9 to 12 inclusive or in one side of the block as shown in Figure 11.

15 The side walls —2— and lining members —18— and —18'— may be provided with holes —19— for receiving bolts or screws for securing said linings to the sides but when the plates —18'— are used as linings 20 for the end walls they may be held in place by the rib members —10—.

When casting the blocks shown in Figures 9 and 10, the various parts of the mold are assembled as shown by full lines in Figures 25 1, 2 and 3 with the base —1— at the bottom so that when the cap section —4— is removed the plastic cement or concrete may be poured and tamped into the mold until the latter is filled to the level of the top, 30 sides —2—, and —3— and posts —8— and when properly leveled off at the top the top section —4— may be placed in operative position under pressure to form the desired smooth surface including the beveled 35 corners formed by the rib —12—.

When the block is properly formed the entire mold may be inverted with the block resting upon the section —4— and as soon as the concrete has set sufficiently to be 40 self-sustaining the base section —1— may be withdrawn and the angular side sections unlocked one from the other to permit them to be swung from the position shown in Figure 5 thus freeing the entire mold except 45 the section —4— from the block which may remain on said section —4— until properly seasoned or if necessary it may be removed from the section —4— and placed upon other supports from seasoning.

50 When it is desired to form the corner block shown in Figure 11 one of the side plates —18— and one of the end plates —6— at the same end of the mold may be removed and interchanged, and the rib section —10— at the same end may also be removed and placed at one side of the corresponding post —8— as shown by dotted lines in Figure 1.

60 Either of the plates —6— and ribs —10— may be thus interchanged to form corner blocks for right hand or left hand turns and for turns in reverse directions.

In forming the half block shown in Figure 12 the partition —5— which might be 65 one of the end plates —6— is inserted in an

upright position transversely of and between the side walls of the mold substantially midway between the end walls as shown by dotted lines in Figure 1 and, therefore, approximately midway between the posts —8— with its vertical ribs —20— facing the similar vertical ribs on one of the end plates —6— so that the intervening space may be filled with concrete to form the half mold shown in Figure 12 but approximately the same process as used in forming the full size block shown in Figures 9, 10 and 11.

It is apparent from the foregoing description that after the block has been formed in the mold and the latter with the block therein inverted, the removal of the base section —1— similarly displaces its lugs —7— and permits the angular sides of the mold to be readily opened about the axis of the connecting hinges by simply unlocking the levers —16—.

It is obvious that the apparatus described is capable of being used in producing not only the various forms of blocks shown in Figures 9 to 12 inclusive but by removing the beveling ribs —12— and —13— the corner of the blocks may be left perfectly plain instead of beveled, said beveling ribs being usually fastened to their respective parts by dowels or equivalent holding means which will permit them to be removed and replaced at will.

The same is also true of the ribs —20— of the lining plates —6— and partition —5—. The channels —20'— formed by the ribs —20— may serve to receive cement in the joints between the adjacent ends of the blocks for holding the blocks against relative transverse movement when built in the wall or if necessary these channels may be left open to form vertical air spaces which will communicate with each other through the several tiers of blocks in the wall and thereby assist the vertical openings —8'— in maintaining a free circulation of air through the completed wall for maintaining the latter in a substantially dry condition under all weather conditions.

What I claim is:

1. A sectional mold for making concrete blocks comprising a base section and a hollow upright section rising from the base section, said base section being provided with an upright core post in spaced relation to the walls of the upright section to form an opening through the concrete block, and a rib on the inner face of the base section extending from the base of the post to one side of the upright section to form a channel in said block leading from said opening to the exterior of the block, said rib being removable and interchangeable to different sides of the post to vary the position of the channel in the block.

2. In a mold for making concrete blocks, a rectangular base section, a rectangular hollow upright section removably mounted upon the base section, core posts mounted on the base section in spaced relation to each other and to the walls of the hollow section and ribs supported on the base section and

movable to different positions relatively to said posts, said ribs extending from the posts to the side walls of the hollow section. 10

In witness whereof I have hereunto set my hand this 3d day of February, 1926.

CHARLES E. SANSON.
